UNITED STATES PATENT OFFICE.

FRANK MOSSBERG, OF ATTLEBORO, MASSACHUSETTS, ASSIGNOR TO MOSSBERG
PRESSED STEEL CORPORATION, OF ATTLEBORO, MASSACHUSETTS, A CORPO-
RATION OF MASSACHUSETTS.

BOBBIN.

1,380,672.

Specification of Letters Patent. Patented June 7, 1921.

Application filed October 15, 1919. Serial No. 330,865.

To all whom it may concern:

Be it known that I, FRANK MOSSBERG, a citizen of the United States, and resident of the city of Attleboro, in the county of Bristol and State of Massachusetts, have invented 5 certain new and useful Improvements in Bobbins, of which the following is a specification.

This invention relates to bobbins more 10 particularly adapted for use on braiding machines; and has for its object to provide such a bobbin having a non-metallic tubular body portion and a metal ratchet-toothed head with specially constructed means for 15 connecting the body to the head by which construction a bobbin will be particularly light and strong rendering it particularly adaptable for use in a braiding machine.

With these and other objects in view, the 20 invention consists of certain novel features of construction, as will be more fully described and particularly pointed out in the appended claims.

In the accompanying drawings:

25 Figure 1— is a sectional side elevation of my improved bobbin.

Fig. 2— is a bottom-end view of the same.

Fig. 3— is a side elevation showing a modified form of my improved bobbin.

30 Fig. 4— is a bottom end of the bobbin shown in Fig. 3.

Referring to the drawings, 10 designates the tubular body portion of my improved bobbin, which is preferably made of wood 35 but which may be made of any suitable non-metallic material. This body portion is provided with a hole 11 through it for the purpose of receiving the spindle of the carrier on which it is designed to be mounted.

40 At the lower end of this body portion is a head-member 12 which is constructed of metal in disk form having its edge or periphery turned downwardly as at 13 and notched to form ratchet teeth 14 which may 45 be engaged in any of the usual ways for the purpose of controlling the let-off motion of the yarn 15 on the bobbin.

In order to securely attach this wooden body-portion to the head, I have provided a 50 ferrule 16 formed of thin metal, and having a laterally-extending flange 17. The lower end of this body portion is fitted tightly into the body of the ferrule and the side wall of the ferrule is forced or bent inward at

intervals as at 18 to serve as a key to secure 55 the two together. The flanged portion 17 of this ferrule is set slightly inwardly as at 19 and is secured to the head member by rivets 20, spot-welding or by any other suitable means.

60 By this construction where the flange is attached to the under side of the head 12 it will be seen that the body portion of the ferrule may be comparatively long thus providing the maximum length of the end bearing 65 for supporting the wooden body in upright position.

In other cases I form the base member of sheet stock and bend the edge 23 downwardly, and form ratchet teeth 24 thereon, 70 and I also form a ferrule 25 with its flange secured to the upper face of the head, and having its body portion 26 arranged to extend downwardly through this head and in this ferrule the lower end of the wooden body 27 is attached.

75 Another advantage in forming the body portion of the bobbin of wood is that in practice it is found that one made of wood will run more satisfactorily on the metal spindle without lubrication than will one made of metal.

80 By forming a bobbin of my improved construction with the body-portion of wood or fiber and the base of metal, it will be seen 85 that the upper part of the body-portion is extremely light in weight which is of great importance in the use of braiding machines, where the direction of travel of the carrier is constantly changing, and where high speed is desired it is necessary that the upper portion of the bobbin shall be as light 90 as possible; then again by connecting this wooden body to a metal head by means of a ferrule the same is extremely strong and durable as well as inexpensive in construction.

95 The foregoing description is directed solely toward the construction illustrated, but I desire it to be understood that I reserve the privilege of resorting to all the mechanical changes to which the device is susceptible, the invention being defined and limited only by the terms of the appended claims.

I claim:

100 1. A braider bobbin having a non-metallic tubular body portion, a metal head at one end of said body having ratchet teeth said

head being provided with a central opening into which one end of said body is fixed.

2. A braider bobbin having a non-metallic tubular body portion, a metal head having teeth formed on its edge, and a bendable metal ferrule into which one end of said body is fixed and the flange of said ferrule is connected to said head.

3. A braider bobbin having a non-metal-

lic tubular body portion, a metal head member having its periphery turned downwardly and ratchet teeth formed therein, a comparatively thin metal ferrule in which one end of said body is secured, and said ferrule having a flange secured to said head. 10

15 In testimony whereof I affix my signature.

FRANK MOSSBERG.
